UNITED STATES PATENT OFFICE.

CHARLES H. CROWELL, OF BROOKLYN, NEW YORK.

TRANSVERSE-DELIVERY GUMMED-STRIP SEVERING AND MOISTENING MACHINE.

1,276,729.

Specification of Letters Patent. Patented Aug. 27, 1918.

Application filed February 24, 1917. Serial No. 150,667.

To all whom it may concern:

Be it known that I, CHARLES H. CROWELL, a citizen of the United States, and resident of the borough of Brooklyn, county 5 of Kings, city and State of New York, have invented a certain new and useful Improvement Relating to Transverse-Delivery Gummed-Strip Severing and Moistening Machines, of which the following is 10 a specification taken in connection with the accompanying drawing, which forms part of the same.

This invention is of especial importance in connection with machines for severing 15 relatively narrow strips from the end of a wide web of gummed cloth or paper tape and then moistening and delivering the same in a direction transverse to the length of the web. This is especially desirable 20 with gummed cloth tape since cloth is most readily woven with relatively stronger warp threads which for best results should extend transversely of the length of the strips of gummed tape formed from the 25 cloth. The web of gummed paper or cloth may be intermittently fed forward to an extent equal to the width of the gummed tape strips which may then be severed from the web and engaged by suitable belts or other 30 delivery devices so as to be moved or delivered in the direction of the length of the severed strips which may be moistened by 35 pressing the gummed sides of the strips in contact with the moistening roll or the like so that when delivered the separate gummed strips are in condition to be used for sealing packages, for instance. The machine may be used to deliver series of strips of different predetermined lengths, 40 such as one long and two short strips for carton sealing, for instance, by mounting a series of supply or web rolls in the machine, these webs of gummed tape having in each case a width corresponding to the desired 45 length of the particular strip in the series and these webs may all be simultaneously fed forward and severed and then delivered successively for such package sealing or other purposes.

50 In the illustrative embodiment of this invention shown in a somewhat diagrammatic way in the accompanying drawings,

Figure 1 is a side elevation partly in section.

55 Figs. 2 to 5 are sectional views showing various cam devices.

Fig. 6 is a side elevation taken from the opposite side of the machine.

Fig. 7 is a partial plan view of the delivery mechanism.

Fig. 8 is a front elevation of the delivery side of the machine; and

Fig. 9 is an enlarged sectional view through the delivery mechanism corresponding to Fig. 7.

The machine may be mounted on a heavy frame 75 of any suitable construction and may have the supply rolls of gummed tape, such as the web roll 47, mounted on the frame as by having the roll shaft 50 removably mounted in suitable bearings and preferably provided with a brake band 49 which may be adjusted so as to prevent undesirable overrunning of the supply rolls. The gummed tape web 48 from this supply roll is preferably intermittently fed to the cutter devices and for this purpose it is usually desirable to have a suitable looper mechanism so that the web may be withdrawn continuously from the supply 75 roll to form a loop or slack portion from which the web may be intermittently fed for severance and delivery. For this purpose suitable primary or supplying rolls, such as a roll 38 which may have its shaft 80 43 mounted in fixed bearings, and the co-operating roll 44 having its shaft 45 mounted in adjustable bearings so that the bite of the rolls may be regulated as by screws 46, may withdraw this web at such 85 rate as is preferably determined by adjustable speed driving mechanism connected to these supplying rolls. The supplying rolls may be geared together as by the gears 161, 142 shown in Fig. 6. From 90 these supplying rolls the web 48 may pass under the looper roll 31 which may have its shaft 33 mounted in bearings in the looper levers 34 at each end of the roll and connected to the axle 35 so that the roll 100 is kept in parallel position as it rises and falls to form and maintain the loop in the web. If desired, the web may pass up from the looper roll through suitable tension rolls or guides 36 and then be engaged and 105 intermittently fed forward by the feeding rolls 37, and 156, which may have its shaft 157 mounted in the adjustable bearings so as to be regulated by the adjusting screws 159, these rolls being geared together as by the gears 155, 160 shown in 110 Fig. 6.

The machine may be driven in any desired way, as for instance from the driving wheel 1 shown in Figs. 1 and 8, which may be connected to the driving shaft 2 at the desired 5 times as by the driving clutch 182 having the annular recess 3 to be engaged by the usual fork or yoke 4 on the clutch lever 5. This driving shaft 2 may drive the parallel transverse shaft 51 as by the meshing gears 10 19, 20, 21, shown in Fig. 1. And as shown in Fig. 6 the shaft 51 may be connected as by the skew gears 52 with the shaft 53 connected as by beveled gears 54 with the main cam shaft 55 extending across the machine. 15 As shown in Fig. 1 another spur gear 8 on the drive shaft 2 may mesh with the gear 9 on the shaft 10 which may as indicated be connected by the beveled gears 11 with the shaft 12 driving through the beveled gears 20 13 the shaft 14 which may be used to operate the moistening and delivery devices. A heavy spur gear 6 on the drive shaft 2 may mesh with the cutter gear 7 connected to the clutch wheel 66 and loose on the cutter 25 shaft 67 so as to intermittently operate the cutter, as will be described hereafter. The primary or supplying rolls 38, 44 may be driven by variable speed gearing shown in Figs. 1 and 8 as comprising the friction disk 30 23 splined on the shaft 51 and normally spring-pressed against the adjustable friction idler wheel 25 as by the spring 74 bearing against the collar 75 on the shaft. The cooperating friction disk 24 may be secured 35 on the shaft 39 connected as shown in Fig. 1 with the shaft 41 by the skew gears 40, for instance, so that the skew gears 42 may connect the lower end of this shaft with the shaft 48 of the supplying roll 38. In this 40 way the supplying rolls are continuously driven at such speed as is determined by the position of the friction idler 25 and this idler is automatically adjusted by the looper roll so as to maintain the loop in the web of 45 gummed tape 48 at about the same length under all conditions. For this purpose the friction idler 25 may be mounted in a slide frame 77 and the rack 27 on the lower part of this frame projecting through the supporting guides or brackets 26 in which the frame slides may mesh with the sector 28 on the shaft 29. This sector may be pivotally connected to the looper rod 30 which 50 may advantageously carry at its lower end the yoke 32 within which the shaft 33 of the looper roll loosely fits. In this way the looper roll can rise a couple of inches as the web is intermittently fed forward for severance and then the looper roll may gradually return to this initial position moving 55 loosely in the yoke so as not to change the adjustment of these available speed devices. If, however, the supplying rolls feed the paper web to the loop at too rapid a rate so 60 that the looper roll falls somewhat beyond

its initial position, the looper rod 30 is drawn downward correspondingly and this through the sector moves the friction idler 25 to the left in Fig. 1 so that the driven friction disk 24 is less rapidly rotated and 70 this correspondingly cuts down the speed of the supplying rolls. In an obvious manner also the rising of the looper roll to a point where it lifts the yoke and looper rod readjusts the friction gearing so as to increase 75 the speed of the supplying rolls and withdraw the web more rapidly from the gummed tape supply roll which is, however, constantly rotated so that undesirable inertia effects are thus avoided. 80

The intermittent feeding rolls for supplying the web to the cutter and delivery devices may be operated from the main cam shaft, if desired, through the feeding cam 144 secured to this shaft so as to cooperate 85 with the cam follower or roll 146 shown in Fig. 3 as mounted on the feeding cam lever 147 normally held down against the cam as by the spring 148. This lever may be connected to the rock shaft 181 carrying the 90 rock arm 145 which may be pivoted to the link 149 so that an intermittent vibratory motion is thus imparted to the link. The upper end of this link may inclose the pivot 150 in the adjustable pivot block 151 in the 95 oscillating slide 158 which swings about the shaft 48 of the feeding roll 37 which carries the ratchet wheel 154. A pawl 153 on this swinging arm 158 cooperates with the teeth of this ratchet so as to feed the ratchet 100 and connected feeding roll forward one or more teeth for every rotation of the feeding cam and this feeding movement may be regulated by adjusting the position of the pivot block 151 in the slide as by the adjusting screw 152 passing through this block and actuated by the nut or head. In this way the amount of web fed forward at each revolution of the cam shaft may be adjusted 105 so that the width of the tape strips severed 110 from the web may be adjusted to suit the requirements of use, it being desirable to have the teeth on the ratchet 154 considerably finer than they are shown in the drawing for greater clearness, so that these teeth 115 correspond to a tape width of a sixteenth or an eighth of an inch or so.

The cutter devices for severing the strips of tape from the web may be of any suitable construction and operation and may comprise a stationary or adjustable block 192, as shown in Fig. 6, of steel or other material with which the movable cutter 72 may accurately cooperate to sever the tape strips from the web. The cutter or knife 72 may 120 as indicated in Figs. 6 and 8, be mounted in a suitable cutter frame 73 so as to slide vertically in guideways, such as 71, in the frame of the machine, and the pivot 70 in the upper part of this cutter frame may con- 125 130

nect thereto the eccentric rods or links 69 coöperating with the eccentrics 68 on the cutter shaft 67 so that every time the cutter shaft rotates through a revolution the knife 5 is accurately and powerfully forced downward to sever a strip from the web and is then returned to its inoperative position shown in Fig. 6. A one-revolution stop motion may be used for actuating the cutter 10 shaft and may comprise as indicated in Fig. 1 a clutch dog 65 coöperating with the internal ratchet on the clutch wheel 66. This clutch dog which may be slidingly mounted in the frame 190 secured to the cutter shaft 15 67 is normally forced outward as by the spring 191 so that it tends to engage the clutch wheel 66. The clutch detent 62 engages the pin 64 on this dog so that the wedging end 63 of the detent forces the 20 clutch dog inward and holds it out of engagement so long as this detent remains in the path of the pin. The detent may be mounted at its lower end on the clutch rod 61 carrying the arm 193, as shown in Fig. 8, 25 which may be pivoted to the clutch link 59 normally pressed upward as by the spring 60. The lower end of this link 59 may as indicated in Fig. 1 be pivoted to the cutter cam lever 58 carrying the cam roll 57 en- 30 gaging the cutter cam 56 on the main cam shaft. In this way the cam shaft at each revolution momentarily withdraws the detent from the path of the pin 64 on the clutch dog allowing this clutch dog to 35 spring out into engagement with the clutch wheel 66 so as to rotate the cutter shaft 67 and effect one reciprocating movement of the cutter before the pin again comes into engagement with the detent and is with- 40 drawn and held stationary in the inoperative position shown in Fig. 1.

The delivery devices preferably comprise sets of coöperating delivery belts of felt or other suitable material as indicated in Figs. 45 7 and 9 so that the severed strips of gummed tape are preferably loosely engaged between these belts and fed forward to the moistening devices. The lower belts 104 may rest upon the guide plate 194 and pass over the 50 belt rolls 115, 117 which may be connected together as by the drive chain 106 passing over the sprockets 105 and 116 on the shafts 86 and 114 of these two belt rolls. The upper delivery belts 100 are mounted on the 55 belt rolls 126, 127, which are vertically movable so as to withdraw this upper delivery belt from engagement with the lower one at the proper times. This may be effected by movably supporting the shafts of these belt 60 rolls, the shaft 108 of the belt roll 126 being as indicated mounted in lifting levers 107 at each end of the roll which may be connected to the rock shaft 122 and the pin 118 in one of these levers may be moved vertically by the projections 119 in the lifting

slide 120. This lifting slide may as indicated in Figs. 5 and 6 have a pin and slot connection with the lifting cam lever 128 swinging about the pin or shaft 131 in the frame and having the cam roll 132 coöperating with the cam 133 and normally held in engagement therewith by a suitable spring diagrammatically indicated as 134. In this way the belt roll 126 is lifted at the proper time and the other belt roll 127 is similarly 7 lifted by its shaft 99 and the coöperating lifting levers 101 operated as by the lifting rod 103 when the other lifting levers swing upward. Thus the upper delivery belts 100 are carried bodily upward and away from 80 the lower belts whenever the lifter cam and lever operate so that a suitable space is then left between the two delivery belts or sets of belts. These delivery belts are preferably both positively operated, the upper 85 belt rolls being, if desired, geared to the lower ones, as shown in Fig. 9. The spur gear 113 on the shaft 114 on the lower belt roll 115 may mesh with the spur gear 112 having its shaft linked to the roll shaft 114. 90 This spur gear may mesh with the gear 111 pivotally mounted in the lifting lever so as to be always in mesh with the spur gear 110. If desired, also, the belt roll 127 may be positively driven by the similar gears 95 95, 96, 97 and 98, the latter being secured to the shaft 99 of the roll.

To facilitate the feeding of the gummed web between the delivery belts when they are separated as indicated in Fig. 6, it is 100 desirable to insert a metallic or other feed plate, such as 173, between these belts and preferably in substantial contact with the lower delivery belts 104 and this plate may be guided and laterally inserted by any 105 suitable devices, such as the brackets 171, in which the plate may be slidingly mounted and which may also carry the shaft 141 connected to suitable sectors 142 meshing with one or more racks 143 on the plate. 110 The sector arm 140 may be pivotally connected with the link 139 pivoted at its other end with the feed plate cam lever 137 which as shown in Figs. 1 and 4 may be pivoted about the pin or shaft 131 and carry the 115 cam roller 136 engaging the cam 135 under the influence of the spring 138. In this way the feed plate is inserted between the belts when they are separated and then when the web has been fed over the plate to the desired extent the plate is withdrawn and the delivery belts preferably brought into substantial contact before severance occurs so as to promote the alinement of the severed strips on the belts by which the strips are 120 delivered to the moistening devices.

These moistening devices may as indicated in Figs. 7, 8 and 9 comprise the moistening roll 17 preferably having longitudinal or other corrugations, depressions or indentations 130

tions and in some cases separated annular recesses 184 may be formed on the moistener with which some or all of the separating fingers 129 may cooperate so as to more effectively disengage the gummed strips from the moistener. A suitable presser 18 preferably cooperates with this moistener so as to firmly press the tape down into moistening contact therewith and the shaft 93 of this presser may be mounted in the presser arms 185 which may be pivoted about the shaft 94 and spring-pressed downward so as to hold the presser in such position as is determined by the adjustable stop pins or screws 184 and cooperating stops 185. These parts are so adjusted that the presser is normally held a few thousandths of an inch away from the moistener when no tape is passing between these rolls and the yielding mounting of the presser allows it to rise when tape comes through the rolls so that the tape is yieldingly but firmly pressed down against the moistener to have its gummed lower surface thoroughly and uniformly moistened by the water or other liquid brought up from the tank 123 by the moistener. The amount of this liquid may be regulated as by the spring pressed doctor 124 and any moisture taken up by the presser 18 may be removed therefrom by the scraper 125 guiding this liquid laterally to such extent that it may drop back into the water tank 123 and minimize undesirable wetting of the tape guided to the moistener through suitable stationary guides, such as 121. For some purposes it is desirable to make the presser roll of water repellent material and for this purpose compressed disks of waxed paper may be forced tightly together and smoothed or finished on their peripheries so as to secure this result which still further lessens the possibility of the presser undesirably taking up water when no tape is passing beneath it. The moistener, and also the presser in some cases, may be positively rotated, and this may be effected by the gear 15 on the shaft 14 shown in Fig. 9 and driven as previously described from the drive shaft of the machine. This gear 15 may mesh with the gear 16 on the shaft 180 of the moistener and the gear 91 on the presser may mesh with the gear 90 on the moistener shaft so that these rolls are driven substantially in unison, the presser roll preferably moving at a slightly greater surface speed in some cases. The spur gear 89 on the shaft 180 may mesh with the gear 88 driving the gear 87 secured to the sleeve 92 loose on the shaft 86 to which the belt roll 88 is connected. A delivery clutch is preferably interposed between this gear and shaft and as shown in Figs. 1 and 7 the clutch wheel or head 88 on the sleeve 92 may be thus connected to the gear 87 and clutched to the shaft 86 when the clutch member 84 is

forced inward by suitable devices, such as the clutch lever 83. The link 81 pivoted to this clutch lever may as shown in Fig. 2 be pivoted to the delivery cam lever 80 turning about the pin 181 and carrying at its other end the roll 79 engaging the cam 78 on the main cam shaft so as to be held in engagement therewith as by the spring 82. In this way the moistener may continuously rotate and the delivery belts may be operated only at intervals after they have been brought into substantial contact on either side of a strip of tape and the latter severed from the tape web.

To briefly summarize the operation of the machine, the web of gummed cloth or paper tape may be continuously withdrawn from the web roll 47 by the supplying rolls 38, 44, so as to form a web loop engaged by the looper roll 31 which regulates the speed of these supplying rolls through suitable friction drive disks 23, 24. The feeding rolls 37, 156 intermittently feed forward the tape web to an extent equal to the width of the separate strips of tape to be severed therefrom. As shown in Fig. 6 the end of the web is fed between the separated delivery belts 100, 104 and over the feed plate 173 inserted between the same. When this feed plate is withdrawn the upper feed belts are brought downward into substantial contact with the gummed tape and the cutter 72 descends to sever the strips. The delivery belts are then actuated as shown in Fig. 9 to carry forward the severed tape strips and moisten the same as they pass between the moistener 17 and presser 18 so that they are ready for application to packages, books, or other articles when they emerge from the machine.

This invention has been described in connection with a number of illustrative embodiments, forms, proportions, materials, arrangements and methods of operation, to the details of which disclosure the invention is not of course to be limited, since what is claimed as new and what is desired to be secured by Letters Patent is set forth in the appended claims.

1. In tape moistening machines, a frame to support a web roll of gummed tape, web feeding devices comprising intermittent feeding rolls and an interposed looper having supplying rolls engaging the web before it reaches the feeding rolls, a power shaft for the machine, friction disks operated by said power shaft and connected to said supplying rolls and an interposed friction wheel regulated by the looper to control the speed of the continuously rotating supplying rolls, a cam shaft connected to said power shaft, a cutter gear connected to said power shaft, a cutter cooperating with said feeding rolls and having a one revolution stop motion controlled by said cam shaft intermittently operating

5 said cutter from said cutter gear, delivery devices comprising upper and lower delivery belts adjacent said cutter, belt lifting devices to lift the upper delivery belt for the entrance of the end of the tape web, a feed plate entering between said delivery belts to facilitate the entrance of the tape web between the same, means controlled by said cam shaft to operate said feed plate 10 and said belt lifting devices and to actuate said delivery belts when a strip of gummed tape has been severed from said web and a continuously rotating moistener roll and a coöperating presser roll adjacent the discharge end of said delivery belts to moisten the tape strips of gummed tape received therefrom.

2. In tape moistening machines, a frame to support a web roll of gummed tape, web feeding devices comprising intermittent feeding rolls, a power shaft for the machine, a cam shaft connected to said power shaft, a cutter gear connected to said power shaft, a cutter coöperating with said feeding rolls and having a one revolution stop motion controlled by said cam shaft intermittently operating said cutter from said cutter gear, delivery devices comprising upper and lower delivery belts adjacent said cutter, belt lifting devices to lift the upper delivery belt for the entrance of the end of the tape web, a feed plate entering between said delivery belts to facilitate the entrance of the tape web between the same, means controlled by said cam shaft to operate said feed plate and said belt lifting devices and to actuate said delivery belts when a strip of gummed tape has been severed from said web and a continuously rotating moistener roll and a coöperating presser roll adjacent the discharge end of said delivery belts to moisten the tape strips of gummed tape received therefrom.

3. In tape moistening machines, a frame to support a web roll of gummed tape, web feeding devices comprising intermittent feeding rolls, a power shaft for the machine, a cam shaft connected to said power shaft, a cutter gear connected to said power shaft, a cutter coöperating with said feeding rolls and having a one revolution stop motion controlled by said cam shaft intermittently operating said cutter from said cutter gear, delivery devices comprising upper and lower delivery belts adjacent said cutter, belt lifting devices to lift the upper delivery belt for the entrance of the end of the tape web, means controlled by said cam shaft to operate said belt lifting devices and to actuate said delivery belts when a strip of gummed tape has been severed from said web and a moistener adjacent the discharge end of said delivery belts to moisten the tape strips of gummed tape received therefrom.

4. In tape moistening machines, a frame to support a web roll of gummed tape, web feeding devices, a cutter coöperating with said feeding devices, delivery devices comprising upper and lower delivery belts adjacent said cutter, belt lifting devices to lift the upper delivery belt for the entrance of the end of the tape web, a feed plate entering between said delivery belts to facilitate the entrance of the tape web between the same, means to operate said feed plate and said belt lifting devices and to actuate said delivery belts when a strip of gummed tape has been severed from said web and a moistener roll adjacent the discharge of said delivery belts to moisten the tape strips of gummed tape received therefrom.

5. In tape moistening machines, a frame to support a web roll of gummed tape, web feeding devices, a cutter coöperating with said feeding devices, delivery devices comprising upper and lower delivery belts adjacent said cutter, belt lifting devices to lift the upper delivery belt for the entrance of the end of the tape web and to actuate said delivery belts when a strip of gummed tape has been severed from said web and a moistener roll adjacent the discharge end of said delivery belts to moisten the tape strips of gummed tape received therefrom.

6. In tape moistening machines, a frame to support a web roll of gummed tape, web feeding devices, a cutter coöperating with said feeding devices, delivery devices comprising upper and lower delivery belts adjacent said cutter, belt lifting devices to lift the upper delivery belt for the entrance of the end of the tape web, and to actuate said delivery belts when a strip of gummed tape has been severed from said web.

7. In transverse delivery tape severing and moistening machines, a frame supporting a roll of gummed tape web, primary supplying rolls engaging and feeding the web from said web roll, a looper device comprising a looper roll engaging said web and having a yoke loosely coöperating with said looper roll and variable speed devices controlled by said looper roll to govern the speed of said supplying rolls, feeding rolls engaging said web beyond the looper and intermittently feeding the same forward to an extent equal to the width of gummed strips desired, an intermittently operated cutter to sever said strips, transversely operating delivery devices to engage the severed strips and deliver them in a direction transversely across the severed end of the tape web and comprising bodily movable delivery belts and a coöperating moistening device comprising a moistener and presser therefor.

8. In transverse delivery tape severing and moistening machines, a frame supporting a roll of gummed tape web, primary sup-

plying rolls engaging and feeding the web from said web roll, a looper device comprising a looper roll engaging said web and having a yoke loosely coöperating with said looper roll and variable speed devices controlled by said looper roll to govern the speed of said supplying rolls, feeding rolls engaging said web beyond the looper and intermittently feeding the same forward to an extent equal to the width of gummed strips desired, an intermittently operated cutter to sever said strips, transversely operating delivery devices to engage the severed strips and deliver them in a direction transversely across the severed end of the tape web and a coöperating moistening device.

9. In transverse delivery tape severing and moistening machines, a frame to support a roll of gummed tape web, a looper device comprising a looper roll engaging said web, feeding rolls engaging said web beyond the looper and intermittently feeding the same forward to an extent corresponding to the width of gummed strips desired, an intermittently operating cutter to sever said strips, transversely operating delivery devices to engage the severed strips and deliver them in a direction transversely across the severed end of the tape web and comprising bodily movable delivery belts.

10. In tape moistening machines, delivery devices comprising upper and lower delivery belts, belt lifting devices to lift the upper delivery belt for the entrance of a tape strip, a feed plate entering between said delivery belts to facilitate the entrance of the tape strip between the same, means to operate said feed plate and said belt lifting devices and to actuate said delivery belts and a continuously rotating moistener roll and a coöperating presser roll adjacent the discharge end of said delivery belts to moisten the tape strips of gummed tape received therefrom.

45 11. In tape moistening machines, delivery devices comprising upper and lower delivery belts, belt lifting devices to lift the upper delivery belt for the entrance of a tape strip, a feed plate entering between said delivery belts to facilitate the entrance of the tape strip between the same, means to operate said feed plate and said belt lifting devices and to actuate said delivery belts.

12. In tape moistening machines, delivery devices comprising upper and lower delivery belts, belt lifting devices to lift the upper delivery belt for the entrance of a tape strip, and means to operate said belt lifting devices and to actuate said delivery belts.

55 13. In tape moistening machines, delivery devices comprising upper and lower delivery belts, belt lifting devices to lift the upper delivery belt for the lateral entrance of a tape strip, means to operate said belt lifting devices and to intermittently actuate said

delivery belts when they engage a tape strip and a continuously operating moistener roll and a coöperating presser roll adjacent the discharge end of said delivery belts to moisten the tape strips of gummed tape received therefrom.

14. In tape moistening machines, delivery devices comprising upper and lower delivery belts, belt lifting devices to lift the upper delivery belt for the lateral entrance of a tape strip, means to operate said belt lifting devices and to intermittently actuate said delivery belts when they engage a tape strip and a continuously operating moistener and a coöperating presser adjacent the discharge end of said delivery belts to moisten the tape strips of gummed tape received therefrom.

15. In tape moistening machines, delivery devices comprising upper and lower delivery belts, means to separate delivery belts for the lateral entrance of a tape strip, means to operate said belt lifting devices and to intermittently actuate said delivery belts when they engage a tape strip and a continuously operating moistener and a coöperating presser adjacent the discharge end of said delivery belts to moisten the tape strips of gummed tape received therefrom.

16. In tape moistening machines, means to intermittently feed a web of gummed tape having a width substantially equal to the length of gummed tape strips desired, a cutter to sever strips from the end of said web and delivery devices to moisten and deliver said severed strips and comprising a pair of coöperating delivery belts, means to separate and bring said belts together to engage a strip, means to drive said belts substantially in unison when in engagement with a strip and moistening devices coöperating with the discharge end of said belts and comprising a positively rotated moistener roll and coöperating presser.

17. In tape moistening machines, means to intermittently feed a web of gummed tape having a width substantially equal to the length of gummed tape strips desired, a cutter to sever strips from the end of said web and delivery devices to moisten and deliver said severed strips and comprising a pair of coöperating delivery belts, means to separate and bring said belts together to engage a strip, and moistening devices coöperating with the discharge end of said belts.

18. In tape moistening machines, means to intermittently feed a web of gummed tape having a width substantially equal to the length of gummed tape strips desired, a cutter to sever strips from the end of said web and delivery devices to moisten and deliver said severed strips transversely of said web and comprising a pair of coöperating delivery belts, means to separate and bring said belts together to engage a strip, and

- moistening devices coöperating with the discharge end of said delivery devices and comprising a positively rotated moistener roll and coöperating presser.
- 5 19. In tape moistening machines, means to intermittently feed a web of gummed tape having a width substantially equal to the length of gummed tape strips desired, a cutter to sever strips from the end of said web and delivery devices to moisten and deliver said severed strips transversely of said web and moistening devices coöperating with the discharge end of said delivery devices and comprising a positively rotated moistener roll and coöperating presser.
- 10 20. In tape moistening devices, means to intermittently feed a web of gummed tape having a width substantially equal to the length of gummed tape strips desired, a cutter to sever strips from the end of said web and delivery devices to moisten and deliver said severed strips transversely of said web and moistening devices coöperating with the discharge end of said delivery devices.
- 15 21. In tape moistening machines, a power shaft and a connected cam shaft, coöperating means to intermittently feed forward a web of gummed tape and a coöperating cutter to sever relatively narrow strips from the web end, delivery devices to engage the severed strips and deliver them transversely of the web end and simultaneously moisten the same, said delivery devices comprising a lower belt to receive the strips, a coöperating upper belt mounted upon rolls and means to simultaneously lift said rolls and belt for entrance of the web end between the belts and means to move said belts substantially in unison when they are in engagement with a severed strip.
- 20 22. In tape moistening machines, means to

intermittently feed forward a web of gummed tape and a coöperating cutter to sever relatively narrow strips from the web end, delivery devices to engage the severed strips and deliver them transversely of the web end and simultaneously moisten the same, said delivery devices comprising a lower belt to receive the strips, a coöperating upper belt mounted upon rolls and means to simultaneously lift said rolls and belt for entrance of the web end between the belts and means to move said belts substantially in unison when they are in engagement with a severed strip.

23. In tape moistening machines, a power shaft and a connected cam shaft, coöperating means to intermittently feed forward a web of gummed tape and a coöperating cutter to sever relatively narrow strips from the web end, delivery devices to engage the severed strips and deliver them transversely of the web end and simultaneously moisten the same, said delivery devices comprising a lower belt to receive the strips, a coöperating upper belt mounted upon rolls and means connected with said cam shaft to simultaneously lift said rolls for entrance of the web end.

24. In tape moistening machines, a power shaft and a connected cam shaft, coöperating means to intermittently feed forward a web of gummed tape and a coöperating cutter to sever relatively narrow strips from the web end, delivery devices to engage the severed strips and deliver them transversely of the web end, said delivery devices comprising a lower belt to receive the strips, and coöperating upper delivery rolls.

CHARLES H. CROWELL.
